[57] CLAIM

The ornamental design for a front panel for a direct
access storage unit for a data processing system, as
shown and described.

DESCRIPTION

FIG. 1 is a front elevational view of a front panel for a
direct access storage unit for a data processing system
showing my new design;

FIG. 2 is a right side elevational view thereof, the left
side elevational view being identical in appearance; and,

FIG. 3 is a top plan view thereof.
The undisclosed rear elevational and bottom plan views
are unornamented.

FIG. 3

FIG. 1

FIG. 2
